ALBERT M. FOWLER AND WILLIAM H. CAULFIELD, OF FAIROAKS, CALIFORNIA, AS
SIGNORS TO CALIFORNIA ALMOND GROWERS EXCHANGE, OF SAN FRANCISCO, CALI-
FORNIA, A CORPORATION OF CALIFORNIA.

ALMOND BLEACHER AND SULPHUR FEEDER.

Application filed January 29, 1921. Serial No. 440,946.

To all whom it may concern:

Be it known that we, ALBERT M. FOWLER and WILLIAM H. CAULFIELD, citizens of the United States, residing at Fair Oaks, county 5 of Sacramento, State of California, have invented certain new and useful Improvements in Almond Bleachers and Sulphur Feeders; and we do declare the following to be a full, clear, and exact description of the same, 10 reference being had to the accompanying drawings, and to the characters of reference marked thereon, which form a part of this application.

This invention relates to improvements in 15 devices for bleaching almonds, this being a process to which almonds are subjected in order to bleach the shells and give them a pleasing appearance which renders them more readily saleable. The process is preferably carried out with the use of sulphur fumes, which of course kill any germ or 20 insect life with which the nuts may be infested, besides giving them a light color as above stated.

25 The process is also adaptable for figs, prunes and other dried fruit and the like.

The principal object of our invention is to provide an apparatus for the purpose by means of which a continuous bleaching process 30 may be carried out, and which will do away with human handling of the products while they are being bleached, and eliminating the possibility of the operator breathing any of the stifling sulphur fumes, as frequently occurs with the crude methods now 35 generally in vogue.

We have also constructed the device so that the length of time during which the products are subjected to the bleaching 40 fumes may be regulated to a nicety.

Another object is to provide a novel means for obtaining and feeding the sulphur fumes.

A further object of the invention is to 45 produce a simple and inexpensive device and yet one which will be exceedingly effective for the purposes which it is designed.

These objects we accomplish by means of such structure and relative arrangement of 50 parts as will fully appear by a perusal of the following specification and claims.

In the drawings similar characters of reference indicate corresponding parts in the several views.

Fig. 1 is a longitudinal view of our apparatus, mainly in section and broken at one point to shorten the same. 55

Fig. 2 is a front end view of the bleaching chamber, showing the sulphur feed device. 60

Fig. 3 is a cross section of the bleaching chamber, taken adjacent the rear end.

Fig. 4 is a sectional view of a sulphur mixer and conveyor.

Fig. 5 is a fragmentary longitudinal section of the rear end of the bleaching chamber. 65

Fig. 6 is an enlarged fragmentary perspective plan of a deflecting board and apron structure. 70

Referring now more particularly to the characters of reference on the drawings, the numeral 1 denotes a covered chamber preferably of concrete, and rectangular in shape, being relatively long compared to its height 75 and width.

Leading to the forward end of this chamber and communicating therewith near the top is a chute 2, covered except at its lower end, which is farthest from the chamber, 80 and which end has a hopper 3 leading thereinto.

Inside this chute, and extending transversely thereof at intervals are concave-faced rollers 4, over which passes an endless travelling belt 5 onto which the hopper discharges and which then passes alternately over plane-faced rollers 6 mounted transversely of the chamber 1 at both ends and arranged in vertically spaced relation, 85 thus passing by steps from top to bottom of the chamber, and finally returning to the outer end of the chute 2.

Alongside the belt in the said chute is a steam pipe 7, provided with spaced slits 95 or orifices 8 positioned to spray the steam onto the belt transversely thereof, so as to spray and dampen the nuts carried thereon and permit the fumes to better act on the shells. 100

To prevent sag of the belt in the chamber, slats 9 are placed under each layer or length of the same between the end pulleys.

It will therefore be seen that with the above described arrangement of the belt, the 105 uppermost layer or length moves toward the rear end of the chamber, passes around the adjacent roller 6, which causes a reversal

of the direction of movement of the belt so that the length below moves toward the front end and over the adjacent roller 6 at that end, when its direction of movement is again reversed and so on, the various pulleys being so arranged that the different lengths of the belt will all lie truly horizontal.

At the front end of the forwardly moving stretches of the belt, except the lowest one, and positioned slightly to the rear of the pulleys and immediately above the belt are V-shaped deflector members 10, positioned with their axes pointing away from said pulleys and extending the entire width of the belt. These members are adapted to brush and deflect the produce carried by the belt onto opposed aprons 10^a which extend parallel to the side edges of the belt and whose upper edges are spaced from the edges of the upper belt but whose lower edges lie inside the vertical plane of the sides of the belt-length below, as clearly shown in Fig. 3.

A similar arrangement of deflectors and aprons is had at the opposite end of the chamber, the deflectors of course pointing in the opposite direction to those just described and being in vertically staggered order relative thereto. By this means the nuts first move from front to rear of the chamber on the uppermost length of belt, are then brushed off onto the belt below, moving then to the front end of the chamber, where they are again brushed off onto the belt below, and so on, gradually working their way from top to bottom of the series of belt-lengths.

The lowest rearwardly moving length of belt discharges directly onto a slatted conveyor-belt 11 which is enclosed in an upwardly extending chute 12 at the upper end of which is a discharge bin 13 into which the bleached nuts raised by this conveyor drop.

The belt 5, or rather the rollers at one end over which said belt passes, and the conveyor 11, are driven in unison and in the proper and common direction by means of any suitable chain or belt drive as shown at 14, preferably exteriorly located, and which may be run at different speeds to suit requirements.

Each belt length runs between upwardly projecting side-boards or guides 15, extending to the aprons 10, and which are fitted with inwardly and downwardly slanting slats 16 which project over the edges of the belt immediately adjacent the upper surface thereof.

A suitable belt-tightener structure as indicated at 17 is fitted to one of the undriven rollers to allow the tension on the belt to be adjusted.

The sulphur fumes are prepared and ad-

mitted to the bleaching chamber in the following manner:—

The powdered sulphur 18, which is not unpleasant nor dangerous to handle, is placed in a bin 19 provided with a stirring mechanism consisting of a pair of endless chains 20 spaced apart, and to which are connected transverse slats 21. It will therefore be evident that with a continuous movement of the chains, the slats are moved through the mass of sulphur, keeping the same well stirred.

In the bottom of the bin is an auger conveyor 22, the sides of the bin sloping down thereto. This auger extends beyond one end of the bin in a tube or enclosure 23, leading and discharging into a furnace 24 having an escape flue 25 leading into the forward end of the chamber 1, the fire in the furnace being made solely by the burning sulphur.

The chains 20 and auger 22 are preferably driven together and from one of the belt-rollers 6 by means of a suitable chain or belt drive as indicated at 26. The enclosure-chamber 12 for the conveyor 11 forms the escapement flue for the fumes, a chimney 27 being provided on top of this chamber to aid the draft and effectually carry away the fumes. By reason of the fact that the sulphur-auger is driven in conjunction with the belts, the feed is automatic, and none is wasted, since as soon as the belts are stopped the supply of sulphur to the burner stops also.

From the foregoing description it will be readily seen that we have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described our invention, what we claim as new and useful and desire to secure by Letters Patent, is:—

1. A bleaching apparatus comprising an enclosed chamber adapted to receive bleaching fumes therein, a plurality of vertically spaced horizontal belt flights in the chamber, said belt flights being arranged to travel in alternate directions and the uppermost receiving the produce to be bleached thereon, and means for passing the produce from the upper to the lower belt flights in successive order at that end of the chamber toward which each such length of belt flight is moving.

2. A bleaching apparatus comprising an enclosed chamber adapted to receive bleaching fumes therein, an endless belt extending lengthwise of the chamber in vertically

spaced and horizontal flights, the alternate flights being arranged to travel in opposed directions, and a conveyor to deposit the produce to be bleached onto the uppermost belt-flight, said conveyor consisting of a flight formed integral with said first named belt.

3. A bleaching apparatus comprising an enclosed chamber adapted to receive bleaching fumes therein, an endless belt extending lengthwise of the chamber in vertically spaced and horizontal flights, the alternate flights being arranged to travel in opposed directions, the uppermost flight of belt being adapted to receive the produce to be bleached thereon, and means for discharging said produce from each belt-flight in turn at the end of its travel in one direction on to the succeeding belt-length below at the beginning of its travel in the opposite direction.

4. A bleaching apparatus comprising an enclosed chamber, a plurality of transversely arranged and vertically spaced rollers at each end of the chamber, an endless belt passing around the rollers in alternate order at each end of the chamber, and means for each belt flight thus formed and adjacent the end of its travel in one direction for deflecting any products thereon to the succeeding flight immediately below and ahead of the rollers and preventing any such products from reaching the rollers.

5. A bleaching apparatus comprising an enclosed chamber adapted to receive bleaching fumes therein, an endless belt extending lengthwise of the chamber in vertically spaced and horizontal flights, the alternate flights being arranged to travel in opposed directions, the uppermost flight of belt being adapted to receive the produce to be bleached thereon, a deflecting member at the rear end of each belt-flight and adapted to brush the produce off the flight and to one side thereof, and aprons at the side of said flights positioned to cause the produce to be deposited upon the succeeding belt-flight below.

6. An almond bleacher including a bleaching chamber, an inclined and enclosed chute leading to said bleaching chamber, an endless belt-conveyor in said chute arranged to receive the almonds thereon, and a steam pipe extending alongside said belt and arranged to spray steam upon the almonds carried thereby.

7. A bleaching apparatus comprising an enclosed chamber adapted to receive bleaching fumes therein, a plurality of vertically spaced horizontal belts in the chamber, the uppermost receiving the product to be bleached thereon and means for passing the produce from the upper to the lower runs of said belts and from the lower run to the upper run of the successive lower belt.

8. A bleaching apparatus comprising an enclosed chamber adapted to receive bleaching fumes therein, endless belts extending lengthwise of the chamber in vertically spaced and horizontal runs, the successive runs being arranged to travel in opposite directions, the uppermost run being adapted to receive the produce to be bleached thereon and means for discharging said produce from each run in turn at the end of its travel in one direction on to the succeeding run below at the beginning of its travel in the opposite direction.

9. In an apparatus for the described purpose, the combination with an outer casing provided with a bleaching chamber, of devices for supplying said chamber with bleaching fumes, means for receiving and moistening the almonds to be treated, propelling means within the bleaching chamber for advancing almonds therethrough in successive lower planes, and means for removing the treated almonds from within the apparatus.

10. An apparatus for bleaching almonds, the same comprising an outer casing providing a bleaching chamber, means for supplying into said chamber bleaching fumes, a series of longitudinally disposed endless conveyors arranged within the bleaching chamber in superposed relation, mechanism for imparting movement to said conveyors, devices for delivering almonds onto the upper run of the uppermost conveyor of the series, devices associated with the discharge end of each run of the conveyors for receiving almonds therefrom, delivering the same onto runs of the conveyors in successively lower planes, and means for receiving the bleached almonds from the lowermost conveyor of the series and delivering the same to the outside of the apparatus.

In testimony whereof we affix our signatures.

ALBERT M. FOWLER.
WILLIAM H. CAULFEILD.
